UNITED STATES PATENT OFFICE.

ROBERT HOPE-JONES, DECEASED, LATE OF NORTH TONAWANDA, NEW YORK, BY CECIL HOPE-JONES, TEMPORARY ADMINISTRATRIX, OF NORTH TONAWANDA, NEW YORK.

ELECTROPNEUMATIC ORGAN-VALVE.

1,199,792.

Specification of Letters Patent.

Patented Oct. 3, 1916.

Application filed November 14, 1914. Serial No. 872,179.

To all whom it may concern:

Be it known that ROBERT HOPE-JONES, deceased, and late of North Tonawanda, in the county of Niagara and State of New York, did invent certain new and useful Improvements in Electropneumatic Organ-Valves; and the following is hereby declared to be a full, clear, and exact description of the same, reference being had to the accompanying drawings, forming a part of this specification, and to the reference-numerals marked thereon.

The present invention relates to the so-called electropneumatic valves used in the construction of organs and it has for an object to provide certain improvements in the arrangement of the parts, whereby their construction is simplified and greater accuracy obtained in their operation.

To these and other ends the invention consists in certain improvements and combinations of parts, all as will be hereinafter more fully described, the novel features being pointed out in the claims at the end of the specification.

In the drawings: Figure 1 is a detail view showing in section a portion of an organ action including a valve constructed in accordance with the invention and illustrating its association with the coöperating parts of an organ with which it is employed; Fig. 2 is a bottom plan view; Fig. 3 is a longitudinal vertical sectional view; Fig. 4 is a cross sectional view taken on the line 4-4' of Fig. 2; Fig. 5 is a plan view of the inner side of the cap showing the reverse side of the portion illustrated in Fig. 2; Fig. 6 is a plan view of the separating piece or spacing member; Fig. 7 is a bottom plan view of the upper section of the casing; Fig. 8 is an enlarged detail sectional view showing the capped end of one of the pole pieces embedded in the upper section of the casing.

Similar reference numerals throughout the several views indicate the same parts.

The valves to which the present invention is applied are employed as primary valves for venting the channels or air passages controlling the secondary valves, the movement of which in turn causes their respective organ pipes to speak. In Fig. 1 one of these valves is shown arranged in its operative position in a wind chest 1 containing its complementary secondary valve

mechanism 2 mentioned above. The primary valve comprises a three-part casing composed of an upper section A, a bottom section B and an intermediate spacer C, the two portions C and B being detachably supported on A and held in proper position thereon by means of dowel pins 3. The upper section A of the casing is attached permanently to the electromagnet 4, the pole pieces 5 of which are embedded in the upper section in such position so that their extremities are slightly out of alinement with the lower face of said section. The shallow recesses thus formed are filled with solder or other non-magnetic metal as indicated by 5' in Fig. 8, the purpose being to prevent the freezing, as it is called, of the armature against the ends of the pole pieces when the iron of these two elements comes into contact.

The windway in the chamber is formed by recesses in the three parts A, B and C, the shape of which is quite important in order that the currents of air may flow into or out of the casing and be quickly distributed on opposite sides of the armature disk 6. The upper section A of the casing is provided with an inlet aperture or port a located between the pole pieces 5 which is closed upon the attraction of the armature 6 by the energizing of the magnet 4. The latter draws the armature securely into engagement with the circular seat 7 formed between the curved ends or channels 8 which are provided to insure the escape of air admitted through the aperture a at all points around the circumference of the armature. The casing A is also provided with an inlet a'. In the bottom portion of the casing B is a recess 9 provided with a space into which projects a pair of curved nipples or bosses 10 provided with apertures or ports 11, on which the armature 6 normally rests. The side walls of the ports 11 are tapered, particularly as shown in Figs. 4 and 5 and are of sufficient height to support the disk 6 a short distance below the ends of the pole pieces and the face of the upper section A of the casing.

The curved nipples 10 form a broad seat for the armature and also serve to distribute the air pressure evenly over a comparatively wide area of the disk and at the same time provide for the maximum opening without necessitating the use of a strong magnet to 110

overcome the air pressure when it is desired to unseat the disk.

In manufacturing these devices it will be appreciated that the faces of the bosses 10 surrounding the ports against which the disk 6 rests should be perfectly plain and smooth and it will be seen that difficulties are encountered in obtaining these conditions when the surfaces are located beneath the 10 upper edges of the side walls of the lower section B of the casing. In order to overcome this difficulty and to simplify the machine operations in making the valve, the faces of the bosses 10 and the face of the 15 edge of the lower member B of the casing are arranged in the same plane, and in order to obtain the required space in which to permit operation of the valve disk 6, a spacing member C is arranged between the parts 20 A and B of the casing. This spacing member C also performs the additional function of centering the disk and is, therefore, provided with inwardly extending projections 12 which will be seen illustrated particularly in Fig. 6. Between the spacing member and the section A of the casing is inserted a fine screen 13 of bolting cloth preventing the entrance of dust or other foreign particles, which might be carried through 30 the passages a or a' and interfere with the proper operation of the armature.

The parts of the casing are preferably made of cast metal and are detachably held together by the dowel pins 3 which are 35 rigidly secured in the portion A of the casing, the parts being held in their relatively operative position by frictional engagement with the pins, so that they may be easily separated by the use of a suitable instrument to permit inspection of the valve disk 40 6. The arrangement of the ports and passages in the parts of the casing is such as to permit the disk 6 to alternately open and close the ports 11 and the passage a with the 45 greatest possible speed and when in one position or the other to close the apertures and prevent the leakage of air.

The invention claimed is:

1. In an electro-pneumatic organ valve, 50 the combination with two recessed members having ports and an apertured spacing member located between the recessed members, of a valve head coöperating with said ports, an electromagnet for operating it and centering projections on the spacing member coöperating with the valve head.

2. In an electro-pneumatic organ valve, the combination with a hollow casing comprising two outer sections provided with opposed ports and an intermediate spacing 60 member, of an electromagnet mounted on one of the outer sections, an armature co-operating therewith and playing between said ports, and fingers on the spacing member coöperating with the armature to center 65 it in respect to said ports.

3. In an electro-pneumatic valve mechanism, the combination with a casing composed of two outer sections and an intermediate spacing member forming a chamber, 70 said sections having inlet and outlet ports, an electromagnet having its pole pieces secured in one of the sections, and a movable armature coöperating with the magnet and with said ports and centering projections on 75 the intermediate member coöperating with said armature.

4. In an electro-pneumatic valve mechanism, the combination with a casing composed of upper and lower sections recessed 80 in their opposing faces and each provided with inwardly projecting portions having faces lying in the planes of the faces of the respective sections, said projections being provided with air ports, of an electromagnet 85 having its pole pieces embedded in the projection of the upper section, an armature coöperating with the ports and magnet and an apertured spacing member separating the two casing sections having centering projections for positioning the armature relatively 90 to said ports.

5. In an electro-pneumatic valve mechanism, the combination with a casing composed of upper, intermediate and lower sections recessed to provide a central chamber, 95 of a boss on the upper section extending into the chamber, and provided with a port, an electromagnet having its pole pieces embedded in said boss, an inwardly extending 100 projection on the lower section also provided with a port, an armature coöperating with said magnet and said ports and means on the intermediate section of the casing serving to center said armature.

CECIL HOPE-JONES,
*Temporary administratrix of the estate of
Robert Hope-Jones, deceased.*
